(57) **CLAIM**

We claim the ornamental design for a two-in-one vibrating ring, as shown and described.

DESCRIPTION

FIG. 1 is a perspective view of the two-in-one vibrating ring; FIG. 2 is a top view of the two-in-one vibrating ring; FIG. 3 is a bottom view of the two-in-one vibrating ring; FIG. 4 is a front view of the two-in-one vibrating ring; FIG. 5 is a rear view of the two-in-one vibrating ring; FIG. 6 is a side view of the two-in-one vibrating ring; and, FIG. 7 is an opposite side view of the two-in-one vibrating ring.

The broken lines in the drawings illustrate environmental structure, and form no part of the claimed design.
